United States Patent Office

Des. 197,271
Patented Jan. 7, 1964

197,271

HANDLE

Gaylord Moncada, Miami, Fla., assignor to Miller Industries, Inc., Miami, Fla., a corporation of Florida

Filed May 13, 1963, Ser. No. 74,850

Term of patent 14 years

(Cl. D10—8)

Fig. 1

Fig. 2

Fig. 3

Fig. 4

Fig. 5

Fig. 6

FIG. 1 is a perspective view of a handle, showing my new design;

FIG. 2 is a side elevational view;

FIG. 3 is a side elevational view looking at the side opposite to that shown in FIG. 2;

FIG. 4 is a front elevational view;

FIG. 5 is a rear elevational view; and

FIG. 6 is a bottom plan view.

I claim:

The ornamental design for a handle, as shown.
